PAGE 2

Fig. 1 is a side elevational view of a trailer body showing my new design.

Fig. 2 also is an elevational view on a slightly reduced scale as seen from the side opposite that shown in Fig. 1.

Fig. 3 is a rear elevational view of my design.

Fig. 4 is a front elevational view of my design.

Fig. 5 is a top plan view of my design on a slightly reduced scale.

Fig. 6 is a side elevational view of my design with the roof extension and the counter elements in folded position.

Fig. 7 is a side elevational view similar to Fig. 2 except that the roof extension and counters are in folded position.

Fig. 8 is a rear elevational view similar to Fig. 3 except that the roof extension and counters are in folded position.

Fig. 9 is a front elevational view of my design similar to Fig. 4 but showing the roof extension in folded position.

Fig. 10 is a top plan view of my design showing the roof extension and counters in folded position.

The wheels, mast and hitch member are shown in broken lines for illustrative purposes only.

I claim:

The ornamental design for a trailer body, as shown and described.
